UNITED STATES PATENT OFFICE.

CHARLES GULDEN, OF NEW YORK, N. Y.

DESIGN FOR A PACKING-JAR.

SPECIFICATION forming part of Design No. 23,382, dated June 19, 1894.

Application filed April 24, 1894. Serial No. 508,881. Term of patent 7 years.

To all whom it may concern:

Be it known that I, CHARLES GULDEN, a citizen of the United States, and a resident of the city, county, and State of New York, have invented and produced a new and original Design for Packing-Jars, of which the following is a specification.

My design consists of a packing jar herein shown and described of essentially the configuration as illustrated in the accompanying drawings, wherein—

Figure 1 is a side view of my design and Fig. 2 a top view of the same.

The leading feature of my design is a straight body portion of cylindrical form in cross section, together with a flaring base, and

a series of beads on the cylindrical portion near the top thereof, the jar being of substantially the same diameter throughout.

In the drawings A represents the body portion of the jar, which is cylindrical in form, B the flaring base, *a* a lip around the mouth of the jar, and *b b* a series of circumferential beads running around the jar near the top thereof.

What I claim is—

The design for a packing jar, substantially as herein shown and described.

CHARLES GULDEN.
